UNITED STATES PATENT OFFICE

97,856

DESIGN FOR A WHEEL OR SIMILAR ARTICLE

George Albert Lyon, Allenhurst, N. J.

Application July 30, 1935, Serial No. 57,867

Term of patent 14 years

To all whom it may concern:

Be it known that I, George Albert Lyon, a citizen of the United States and residing in the city of Allenhurst, in the county of Monmouth and State of New Jersey, have invented a new, original, and ornamental Design for a Wheel, or Similar Article, of which the following is the specification, reference being had to the accompanying drawing, forming a part thereof.

On the drawing:

Figure 1 is an outer side elevational view of a wheel embodying my design.

Figure 2 is a side elevational view of the device shown in Figure 1, taken from the left hand

side of Figure 1, with the rim and hub or central part of the wheel being shown partly in section substantially as indicated by the line II-II of Figure 1 to better illustrate the arrangement.

Figure 3 is a fragmentary profile view showing in outline form the contour of my novel wheel design, and showing clearly an annular shell-like ring applied over the central portion of the disk-like member.

I claim:

The ornamental design for a wheel or similar article substantially as shown and described.

GEORGE ALBERT LYON.
